SIGNORS TO R. A. BYRNE, OF PHILADELPHIA, PENNSYLVANIA.

TENSIONING DEVICE FOR SCISSORS AND SHEARS.

No. 799,882

Specification of Letters Patent.

Patented Sept. 19, 1905.

Application filed January 12, 1904. Serial No. 188,771.

To all whom it may concern:

Be it known that we, JOHN J. ANDERSON and JOSEPH F. FISHER, citizens of the United States, residing at Fremont, in the county of 5 Sandusky and State of Ohio, have invented new and useful Improvements in Tensioning Devices for Scissors and Shears, of which the following is a specification.

This invention relates to improvements in 10 scissors and shears, and has for its object the provision of a new and novel tensioning means whereby the cutting edges of the blades are held firmly against each other to insure at all times even and uniform cutting, and a further 15 object of the invention is to lessen the wear on the head of the pivotal screw.

The invention consists in the novel construction and arrangement of the several parts of the device as will be hereinafter described, 20 illustrated in the drawings, and more particularly pointed out in the claim hereunto appended.

In the drawings, Figure 1 is a perspective view of a pair of shears having our improved 25 tensioning device applied thereto. Fig. 2 is a longitudinal sectional view taken on the line αx , Fig. 1. Fig. 3 is a top view of one of the blades, the tension-plate being removed therefrom. Fig. 4 is a detail of the tension- 30 plate, partly broken away, showing the screw-threaded opening or aperture for the tension-screw; and Fig. 5 is a vertical longitudinal section thereof.

Referring to the several views, the numeral 35 1 indicates a pair of scissors or shears, 2 the bottom or right-hand blade, and 3 the top or left-hand blade. The blade 2 is provided with the usual screw-threaded opening 4 for the reception of the screw-threaded end 5 of the pivotal 40 screw 6. This blade is of the same construction as the corresponding blade of the ordinary scissors or shears and needs no further description.

The top or left-hand blade 3 is provided 45 with a suitable opening 7, through which the body of the pivot-screw 6 is passed, and is substantially of the same construction of the corresponding blade of the ordinary scissors or shears, with the exception that the opening 50 7 is not screw-threaded. This opening 7 is slightly larger than the body of the pivotal screw to permit the free passage of said screw-body therethrough.

The numeral 8 indicates a suitable plate,

preferably curved, as shown, having therein 55 an opening 9, also slightly greater than the diameter of the body of the pivotal screw 6, but smaller than the diameter of the head of said screw. One end 10 of this plate 8 is preferably forked or bifurcated for the purpose 60 of providing a firm bearing for the end of said plate 8, while near the opposite end 11 is a screw-threaded opening or aperture 12 for the reception of a set-screw 13.

The numeral 14 indicates a seat in the outer 65 face of the blade 3, into which the end of the set-screw 13 sets when the device is applied to a pair of scissors or shears.

This device is applied to the scissors or shears in the following manner: The blades 70 are placed on one another in the usual way, and the tension-plate 8 is placed on the upper or left-hand blade, curve up, with its opening 9 registering with the openings 7 and 4 of the blades 3 and 2, respectively. The pivot- 75 screw 6 is then passed into these openings and its screw-threaded end 5 screwed into the opening 4 in the blade 2 until the end of said screw is flush with the outer surface of the blade 2 and the head of said screw rests or impinges 80 against said plate 8. The set-screw 13 is then placed in the aperture 12 and turned therein until the end thereof sets in the seat 14 in the face of the blade 3, as is apparent, and when thus assembled said scissors or shears are 85 ready for use. When for any reason it is desired to increase the tension of the shears or scissors, the set-screw 13 is turned down hard against said blade 3, thereby, by reason of being connected with said plate by screw- 90 threads, raising the end 11 and forcing the plate upward against the under side of the head of the pivotal screw, and thereby forcing the cutting edges of the two blades together, whereby the tension of the shears or scissors 95 may be set to any desired degree—that is, said blades may be so adjusted that there will be no tension at all or they may be tensioned to any degree up to a point where it will be difficult to operate the shears. This latter de- 100 gree of tension is never of course used, but the extent of movement of the device is desirable for the reason that no matter how great the wear may be on the device such wear can never be so great as to prevent the proper 105 tensioning of the blades, as will be evident. When for any reason it is desirable to loosen the tension of the blades, the same is accom-

plished by turning the set-screw up until the desired decreased tension is secured.

It is evident that this device may be applied to old as well as new shears by lengthening 5 the pivot-screw sufficient to permit the plate 8 to set under the head thereof.

Having thus described our invention, what we claim, and desire to secure by Letters Patent, is—

- 10 In a pair of scissors or shears, the combination with a pair of blades, one of said blades having a plain opening and the other a screw-threaded opening therein, and a pivotal screw of a greater length than the combined thickness 15 of the two blades, said pivotal screw setting through the plain opening in one blade and having its end secured in the screw-threaded opening in the other blade, of a curved tensioning-plate having a plain opening therein and a screw-threaded aperture at or near one end thereof, and its opposite end forked or bifurcated to provide two fulcrum- 20

points upon which said plate rests when tilted, and a thumb-screw adapted to set in the screw-threaded aperture, said tensioning-plate being adapted to set under the head of said pivotal screw with its two fulcrum-points resting on the adjacent blade, whereby, when said thumb-screw is turned down against the adjacent blade, the tensioning - plate will be 25 forced up against the under side of the head of the pivotal screw, drawing the blades together and increasing the tension thereof, and loosening the tension of said blades when the thumb-screw is loosened. 30

In testimony whereof we have signed our names to this specification in the presence of two subscribing witnesses.
